(57) **CLAIM**

The ornamental design for a portable electronic device bezel, as shown and described.

DESCRIPTION

FIG. 1 is a front and right side perspective view showing our new design for the portable electronic device bezel.

FIG. 2 is a front view thereof.

FIG. 3 is a top view thereof.

FIG. 4 is a bottom view thereof.

FIG. 5 is a rear view thereof.

FIG. 6 is a left side view thereof; and,

FIG. 7 is a right side view thereof, being the mirror image of FIG. 6.

The broken lines outlining the bezel represent the boundaries of the claimed design, while the broken lines are included for the purpose of illustrating environmental structure and portions of the bezel, they form no part of the claimed design.
